BERT C. BAUM, OF FORT WAYNE, INDIANA, ASSIGNOR OF TWO-TENTHS TO KENT SWEET, TWO-TENTHS TO WARREN V. SWEET, TWO-TENTHS TO LEONARD SYKES, AND ONE-TENTH TO OMAR K. GARRARD, ALL OF FORT WAYNE, INDIANA.

IRONING MACHINE

Application filed June 30, 1924. Serial No. 723,087.

The invention relates to ironing machines and its object is to provide a simple, cheap and efficient machine.

Another object is to provide an ironing machine with a novel, simple and efficient driving mechanism.

The invention consists in the novel construction, arrangement and combination of parts hereinafter described and illustrated in the drawings, in which illustrative drawings:

Figure 1 is a front elevational view, partly in section, of a machine embodying the invention; Fig. 2 an enlarged, sectional view of the clutch operating mechanism; Fig. 3 an end view of the support for the inner end of the lower roll; Fig. 4 an outer end view of the lower roll, Fig. 5 a sectional view on line 5—5 of Fig. 4.

Referring to the illustrative embodiment of the invention 1 is the main frame or standard of the machine having suitable legs 2 with castors 3 to form a base of suitable weight to cause the machine to stand firmly on the floor.

The frame or standard 1 is preferably hollow to house certain of the operating parts about to be described. In the upper portion of the frame is a shaft 4 carried by the bearings 5 and 20 formed on the frame. A worm gear 6 is loose on this shaft and a flange 7 projects laterally from its forward peripheral edge, the inner peripheral base 8 of which is bevelled, thus causing the flanged worm gear to be a clutch member as well, and on the outer peripheral face of which teeth are formed to form a gear 9 on the worm gear 6 that meshes with a pinion 10 secured to a hollow shaft 11. The shaft 11 is revolvably mounted on a pipe or other hollow member 12 fixed in the main frame and projecting forwardly therefrom, its outer end being supported by the bracket arm 13 which projects from the top of the main frame or standard 1. In the present embodiment of the invention the member 12 serves as a gas burner to heat the upper roll 14 that is revolvably mounted on the member. The inner end of the roll 14 is apertured to receive the outer end of an arm 15 which projects from the shaft 11 and by which arm the roll is caused to rotate.

The worm gear 6 is in mesh with a worm 16 suitably mounted in the standard 1 and 35 adapted to be driven by an electric motor 17 suitably supported on the standard, the motor being suitably connected to the worm for said purpose, as by pulley wheels on the motor shaft and worm respectively and a 50 belt engaged thereon (not shown), the latter mechanism being covered by the cover 18 for the sake of safety to the operator.

A clutch member 6^a is keyed to the shaft 4 and is slidable along the shaft toward the 65 clutch member 6. A coiled spring 6^b encircles the shaft between the two clutch members and tends to maintain them in disengaged position. A washer 19 is placed between the clutch member 6^a and the bearing 20.

Pins 21 are longitudinally movably supported in apertures 22 formed in the bearing 20, the inner ends of which pins abut the opposed face of the washer 19. The opposite ends of the pins project from the bearing and abut the face of a washer 23 which abuts the opposed face of an internally threaded collar 24 engaged on a threaded portion 25 of the shaft 4, borne by the bearings 5 and 20 and by the bearing 26 carried by a bracket 27 adjustably secured to the bracket 28 that is secured to the standard 1.

A bearing 29 is eccentrically mounted on the shaft 4 adjacent to the collar 24 and is 35 connected to the collar by the pins 30. A wheel-like member 31 is revolvably mounted upon this bearing 29 and one end of a cylinder 32 is secured to the periphery of the member 31, a similar member 33 being secured adjacent the opposite end of the cylinder and revolvably mounted upon a bearing 34 that is eccentrically mounted on the shaft 4 and is held in fixed position relatively to the bearing 29 by the tie bar 35 secured to 50 it and to the bearing 29. Suitable padding is secured about the cylinder 32. Suitable members 36 are inserted at selected points within the cylinder to reinforce the same.

A disk 37 is secured by the set screw 37^a to the shaft 4 adjacent the outer face of the member 33, the disk having a slot 38 therein (Fig. 4) in which is engaged a screw 39 that projects from the face of the member 33.

An arm 40 projects laterally from the

projecting end of the bearing 29, and one or more apertures 41 are formed in the arm in any one of which a bolt may be inserted for connecting the upper end of a link 42 to the arm. The link extends downwardly through a slot 43 in the wall of the standard 1, and its lower end is pivoted to one end of a lever 44 pivoted at 45 to one of the legs of the base. The outer end of the lever 10 is adapted to be engaged by the foot of the operator. A spring 46 is placed on the link between the lever and the base to oppose the upward movement of the link.

In operation, with the electric motor in 15 operation, the latter drives the worm and the combined gear, and clutch member 6 is thereby driven to cause the upper hot roll to rotate continuously while the power is turned on. When the operator depresses the 20 foot lever, the link is moved upwardly to cause the bearings 29 and 34 to rotate or swing upwardly and rearwardly on the shaft 4. Since these bearings are eccentrically mounted on the shaft their upward 25 movement will cause the cylinder 32 to move toward and into contact with the upper hot roll, the point of contact being behind the vertical plane of the axis of the hot roll. The swinging movement of the bearing 29 30 causes the collar 24 to rotate and travel on the threaded portion of the shaft 4 toward the bearing 20. The pins 21 are thereby moved longitudinally to cause the clutch member 6^a to frictionally engage the combined gear-clutch member 6, whereupon the 35 shaft 4 will be rotated counter-clock-wise and in a direction opposite to the direction of rotation of the roll 14. Since the disk 37 is secured to the shaft, it, by means of 40 the pin 39 and slot 38, drives the cylinder, the slot accommodating the eccentricity of the cylinder. In practice the upper roll travels about five times as rapidly as the lower roll thus accomplishing a very desirable 45 ironing effect or polish on the materials.

The control of the lower roll is positive and practically instantaneous. Since the lower roll, as it is moved toward the upper 50 roll, travels upwardly and rearwardly in the arc of a circle, the forward edge of the article to be ironed may be placed on the lower roll and moved by the roll as the latter moves toward the upper roll and thereby 55 be carried under the upper roll so that the extreme forward edge of the article will be ironed immediately.

The lower roll may be moved toward the upper roll as the covering wears out on the 60 lower roll by adjusting the rod 27 in the bracket 28, sufficient play being provided in the bearings 5 and 20 to permit of this adjustment.

It will be noted that the instant the pedal 65 is released, the springs 6^b and 46 restore

the roller 32 to normal position. The parts are of light construction so that the roller is easily swung into engagement with the heated member 14.

What I claim is:

1. In an ironing machine, the combination of a heated member, a revoluble shaft, a roller supported on the shaft and adapted to be swung thereon into contact with the heated member, a driven member loosely mounted on the shaft, means responsive to the swinging movement of the roller to connect the shaft to the driven member and means connecting the shaft to the roller for driving the roller. 80

2. In an ironing machine, the combination of a heated member, a revoluble shaft, a roller supported on the shaft and adapted to be driven thereby, the roller being adapted to be swung on said shaft into contact with the heated member, a clutch member loosely supported on the shaft, means to rotate the clutch member, a second clutch member keyed to the shaft and adapted to engage the loose clutch member, and means having engagement with the keyed clutch member and responsive to the swinging movement of the roller to cause the clutch members to engage. 85

3. In an ironing machine, the combination of a heated member, a revolubly mounted shaft, a roller eccentrically mounted on the shaft and adapted to be swung thereon into engagement with the heated member, driving means connecting the shaft 90 to the roller, a driven clutch member loosely mounted on the shaft, a slideable clutch member secured to the shaft, a travelling member on the shaft having a connection to the slideable clutch member and adapted to cause the latter member to engage the loose clutch member, said travelling member being caused to move by the swinging movement of the roller. 100

4. In an ironing machine, the combination of a heated member, a revolubly mounted shaft, a pair of bearings eccentrically mounted on the shaft, and adapted to be rotated thereon, a roller revolubly mounted upon the bearings, means connecting the roller to the shaft for rotating the roller, a driven clutch-member loosely mounted on the shaft, a slideable clutch-member adapted to connect the loose clutch member to the shaft, a travelling member 110 revolubly mounted on the shaft having a connection to the slideable member and to one of the said bearings and adapted when said bearing is rotated to cause the clutch members to engage. 115

5. In an ironing machine the combination of a revolubly mounted heated member, a revolubly mounted shaft, a driven gear-carrying clutch member loosely mounted on the shaft and adapted to cause the heated 120 125 130 member to rotate. 135

member to rotate, a slideable clutch member connected to the shaft and adapted to connect the gear-carrying clutch member to the shaft, a roller eccentrically mounted on the shaft and adapted to be swung upon said shaft into engagement with the heated member and means responsive to the swing-

ing movement of the roller to cause the two clutch members to engage.

In witness whereof I have hereunto subscribed my name this 27th day of June, 1924.

BERT C. BAUM.
